UNITED STATES PATENT OFFICE

130,069

DESIGN FOR A SPECTROSCOPE

Kennard W. Harper, East Aurora, N. Y., assignor
to Spencer Lens Company, Buffalo, N. Y., a
corporation of New York

Application April 2, 1941, Serial No. 100,100

Term of patent 14 years

To all whom it may concern:

Be it known that I, Kennard W. Harper, a citizen of the United States of America, residing at East Aurora, in the county of Erie and State of New York, have invented a new, original, and ornamental Design for a Spectroscope, of which the following is a specification, reference being made to the accompanying drawing forming a part thereof.

Fig. 1 is a perspective view of a spectroscope showing my new design;

Fig. 2 is a plan view thereof; and
Fig. 3 is an end view thereof.

I claim:

The ornamental design for a spectroscope, substantially as shown.

KENNARD W. HARPER.
